United States Patent Office

Des. 192,075
Patented Jan. 16, 1962

192,075

CHAIR

Wayland B. Parker, 427 2nd Ave., Olean, N.Y.

Filed Dec. 28, 1960, Ser. No. 63,363

Term of patent 7 years

(Cl. D15—1)

FIG. 1

FIG. 4

FIG. 5

FIG. 2

FIG. 3

FIGURE 1 is a front perspective view of a chair embodying my design.

FIGURE 2 is a plan view of the arcuate top member, FIGURE 3 is a front elevational view thereof,

FIGURE 4 is a side view of the arcuate top member; and

FIGURE 5 is a cross-sectional view taken along the line 5—5 of FIGURE 3 and looking in the direction of the arrows thereof,

The dominant feature of my design resides in that portion shown in full lines on the drawing.

I claim:

The ornamental design for a chair, substantially as shown and described.
